UNITED STATES PATENT OFFICE

2,422,427

ELECTRONIC DISCHARGE DEVICE

Harry L. Louden, Cleveland, Ohio, assignor to
General Electric Company, a corporation of
New York

Application January 21, 1944, Serial No. 519,112

4 Claims. (Cl. 250—165)

1

This invention relates to the activation of electrodes of electric discharge devices, and especially to activation effected by matter in vaporous or suspended form that is introduced or liberated into a discharge device envelope to come in contact with an electrode to be activated. The liberation of such matter may take place after the initial evacuation of the discharge envelope, and matter thus disseminated in the envelope may also serve the purpose of a getter to clean up residual gas or vapor and improve the vacuum. The invention is here explained with particular reference to its employment in the manufacture of a simple type of photocell having a cathode surfaced with an antimony and cesium combination; but it will be understood that it is applicable to other types of discharge devices, such as electron multipliers, for example. Likewise, it is applicable to electrodes surfaced with other combinations besides antimony and cesium, such as bismuth and cesium, antimony and rubidium, or any useful combinations of vaporizable first group metal with metal of the fifth group of the periodic system. Various features and advantages of the invention will become apparent from the description of a species and form of embodiment, and from the drawings.

The single figure of the drawing shows a vertical longitudinal section through one form of photocell device, partly of vitreous construction, which conveniently embodies the invention.

A photocell device X is shown in the figure as comprising a short vitreous or glass envelope tube 10 having its ends sealed by fusion to the margins of abutting annularly embossed discs or electrode headers 11, 12 of sheet metal (such as chrome iron or "Allegheny 55," as it is commercially known), generally similar to those used for the ends of the tubular incandescent lamps commercially known as "Lumiline" lamps. The cathode header 11 which appears at the bottom in the figure carries a coaxial sheet metal cathode disc 13 (as of Nichrome or nickel) welded thereto and shown with its outer edge turned up toward the anode header 12. As shown, a glass appendix or exhaust tube 15 is attached or sealed by fusion to the outer side of the centrally apertured header 11, substantially coaxial with its aperture and with a corresponding central opening 16 in the disc 13. The anode header 12 which appears at the top in the figure is not apertured, but carries or embodies a central container 18 in which is a charge or pellet 19 which yields metallic cesium vapor under heat, such as a well-known mixture of cesium chro-

mate with silicon as a reducing agent. Current connections 20, 20 are shown welded to the headers 11, 12.

As thus far described, the cell device X corresponds substantially to those heretofore manufactured. In accordance with the present invention, however, this device X differs importantly from the old cells just referred to as regards the container 18 for the cesium mixture, and associated features.

As shown in the figure, the end header 12 which carries the container 18 has a reentrant, inward projecting disc-like central area 21 coaxial with the tube 10, and a sheet metal cover 22 of disc-like form coacts with this area 21 to enclose and contain the charge 19 between them. Accordingly, at least one of the disc-like parts 21, 22 is recessed or dished to provide the required room. As here shown, the header wall area 21 is spherically recessed internally for this purpose, while the dished cover 22 is larger than the area 21 and has its margin 23 turned back on a bevel to extend outward and rearward toward the header 12 around its area 21, somewhat like a pie-pan rim—the central area inside the rim 23 being shown flat. The cover 22 may be spot-welded to the header 11 at the edge of the area 21, at one or more points 24 in its circumference, so as to permit escape of matter outward from the periphery of the recess where the cover is unattached to the metal wall, as is necessary when the charge 19 in the container 18 is heated and flashed. This allows escape not only of the alkali metal vapor formed by flashing the charge 19, but also of getter vapor from a small charge 25 (such as a bar of metallic bismuth) which may be enclosed in the container 18 along with the charge 19, and may be heated, flashed, and vaporized at the same time. The rim 23 serves to deflect back toward the header wall around the recessed and reentrant area, away from the cathode 15 and cathode header 11, the vapor and any solid matter or residue that may escape peripherally outward from between the parts 21, 22. Thus the vapor is prevented from blowing directly on the cathode 13 and depositing there too heavily or unevenly, and solid particles escaping from the container 18 are caused to deposit on the header 12 and prevented altogether from reaching the cathode 15 to deposit there—which would render the cell X practically useless.

In manufacturing the cell device X above described, the cathode disc 13 is welded to the header 11 and the tube 10 is sealed at one end to this header, the cathode disc 13 is surfaced with

a thin coating of antimony thermally deposited thereon, the charges 19, 25 may be put in place and the cover 22 secured to the edge of the area 21 over them (care being taken not to flash either of the charges 19, 25 in welding on the cover 21), and the header 12 is sealed to the end of the tube 10, the glass tube 15 being also sealed to the header 11. In its subsequent processing, the cell device X is baked and exhausted, and the charges 19, 25 are "flashed" by heating the header 12, as by means of a (hydrogen) gas torch or a high frequency coil, thus forming metallic caesium and barium vapors and liberating and introducing them from the container 18 into the cell X, as already described. Concurrently, the cell X is cooled by air jet (s), except where thus heated. This results in deposition of condensed metallic caesium on the glass walls 10 and on the antimony-coated surface of the cathode 13, in amounts materially exceeding what is needed to unite or combine with the antimony. The cell X is then heated in an oven to a sufficient temperature (such as some 225° C.) to revaporize the excess caesium and drive it out of the cell via the tube 15, after which the cell X is tipped or sealed off short from the tube 15 as indicated in dotted lines, leaving the resulting exhaust tip 26 sheltered in the central cavity in the header 11.

What I claim as new and desire to secure by Letters Patent of the United States is:

1. In a discharge device, the combination with a discharge envelope having a reentrant wall area and an opposed cathode surfaced with reactive metal, of a charge adjacent said reentrant wall area which yields alkali metal vapor under heat, and a dished cover enclosing said charge between the same and said reentrant wall area, while permitting escape of matter outward from between them, the margin of said cover extending outward and rearward toward the envelope wall around said reentrant area.

2. In a discharge device, the combination with a discharge envelope having an internally recessed sheet metal wall and an opposed cathode surfaced with reactive metal, of a charge in said recess which yields alkali metal vapor under heat,

and a sheet metal cover covering over said charge and said recess and welded to said cover at the edge of the recess, but permitting escape of matter outward from the periphery of the recess where it is unattached to the metal wall.

3. In a discharge device, the combination with a discharge envelope having an internally recessed sheet metal wall and an opposed cathode surfaced with reactive metal, of a charge in said recess which yields alkali metal vapor under heat, a sheet metal cover covering over said charge and said recess and welded to said cover at the edge of the recess, but permitting escape of matter outward from the periphery of the recess where it is unattached to the metal wall, and means also carried by said metal wall for deflecting away from said cathode matter escaping as aforesaid.

4. In a discharge device, the combination with a discharge envelope comprising a vitreous tube with a sheet metal cathode header sealed to one end thereof, of a sheet metal anode header sealed to the other end of said tube and having a reentrant wall area, a charge adjacent said reentrant wall area which yields alkali metal vapor under heat, and dished sheet metal cover welded to said anode header at the edge of its said reentrant wall area and enclosing said charge, but permitting escape of matter outward from said area where it is unattached thereto, the margin of said cover extending outward and rearward toward said header around said area.

HARRY L. LOUDEN.
